UNITED STATES PATENT OFFICE.

GEORGE W. BAILEY, OF ARLINGTON, VIRGINIA.

PERPETUAL CALENDAR.

1,109,814.

Specification of Letters Patent.

Patented Sept. 8, 1914.

Application filed April 29, 1914. Serial No. 835,203.

To all whom it may concern:

Be it known that I, GEORGE W. BAILEY, a citizen of the United States, residing at Arlington, in the county of Alexandria and State of Virginia, have invented certain new and useful Improvements in Perpetual Calendars, of which the following is a specification, reference being had to the accompanying drawings.

10 This invention relates to calendars of that type generally designated as "perpetual," and has for its primary object to produce a calendar of this character whereby the month indicating numerals may be easily 15 and quickly transposed or changed and properly located with respect to the week days.

The invention has for a further object 20 to produce a perpetual calendar having interchangeable bars provided with numerals whereby a complete monthly calendar for thirty-one, thirty, twenty-nine or twenty-eight days may be easily and quickly produced and the numerals properly arranged 25 with relation to the week day characters.

The invention has for another object to 30 provide a calendar of the above character which is extremely simple in its construction, very serviceable in practical use and capable of manufacture at comparatively small cost.

With the above and other objects in view 35 as will become apparent as the description proceeds, the invention consists in certain constructions, combinations and arrangements of the parts that I shall hereinafter fully describe and claim.

For a full understanding of the invention, reference is to be had to the following 40 description and accompanying drawing, in which—

Figure 1 is a front perspective view of a calendar constructed in accordance with the preferred embodiment of my invention; 45 Fig. 2 is a vertical section thereof; Fig. 3 is a rear elevation thereof; Fig. 4 is a detail perspective view of one of the numeral bars; Fig. 5 is a fragmentary perspective view looking at the rear side of the base. 50 Fig. 6 is a fragmentary view of one of the date-carrying bars. Fig. 7 is a detail perspective view of a month indicating block.

In the accompanying drawings wherein I have illustrated my invention in its pre-

ferred form, a base or frame is provided 55 consisting of the upper and lower parallel horizontal bars indicated at 5 and 6 respectively. These bars are connected at their ends by the parallel vertical bars or cleats 7, said cleats projecting beyond the 60 rear faces of said horizontal bars. The upper bar 5 is provided upon its lower edge with a forwardly inclined or beveled rib or projection 8 upon which the week day indicating letters as shown at 9 are printed 65 or otherwise delineated.

To the rear face of the upper horizontal body bar 5, a plurality of wire loops or staples 10 are secured and a series of pins 11 corresponding in number to the staples 10 are fixed in the lower horizontal bar 6 and project rearwardly therefrom. A plurality of date bars 12 corresponding in number to the days of the week, are provided upon their upper ends with pins or 70 studs 13 which are adapted to be engaged in the respective staples 10. Each of the bars 12 is provided with spaced openings 15 in its lower end, with the exception of the bar bearing the numeral 1, which has 75 only one opening 15' formed therein. These openings are adapted to engage the pins 11 projecting from the rear face of the lower base bar 6. Four of the bars 12 are provided with numerals indicated at 14 upon 80 one face. The other three bars have numerals 14' on both faces, there being four numerals on one face, and five on the other. By proper arrangement of these three bars with the others, as hereafter set forth, a 85 calendar for any month, irrespective of the number of days, may be obtained.

In Fig. 1 of the drawings, I have shown the bars 12 properly arranged upon the base of the calendar for a month of thirty-one days, in which arrangement, it will be noted that all three of the numeral bars have their faces whereon the five numerals 14' are provided visually disposed. If, however, the month contains only thirty days, 90 one of the bars is reversed so as to expose that side to view which contains the four numerals, 3, 10, 17 and 24. For the month of February, occurring in a leap year, 95 wherein the month has twenty-nine days, two of the bars are reversed, only that having the five numerals commencing with 1, 100 being exposed. For the month of February,

not occurring in a leap year, all of the three bars are reversed so as to show a month having twenty-eight days.

It will be understood that in assembling the date bars upon the base or frame of the calendar, the bar having the numeral 1 thereon is first arranged in line with the proper week day letter 9, and the other bars then disposed in proper sequence, the studs 5 on the bars being engaged with the respective staples 10 and the openings in the lower ends of said bars receiving the pins 11. If the first of the month falls on Saturday, the bar bearing numeral 1 is properly 10 placed, and other the upper openings 15 in the date bars are engaged with the pins 11. When the first of the month falls on any other day, those date bars which are arranged on the right of the bar containing 15 the numeral 1, (looking from the front) have their lower openings 15 engaged with the pins 11 while those bars on the left thereof have the upper openings engaged with 20 said pins.

25 To one of the cleats or bars 7 of the calendar base, one end of an elastic strap 16 is secured, the other end of said strap being provided with a suitable hook 17 for engagement with the keeper 18 on the opposite vertical bar 7. It will be understood that 30 this elastic strap is provided for the purpose of holding the bars 12 in position and preventing their accidental displacement. The upper edge of the lower base bar 6 provides 35 a ledge 19 for pencils, pens etc. It will be found of convenience when the device is used as a desk calendar. To the rear face of the upper base bar 5, the ends of a chain indicated at 20 may be attached whereby the 40 calendar may be suspended upon a wall.

The upper base bar 5 is provided in its front face with an elongated horizontally extending recess to receive a month block 21. It will be understood that three of these 45 blocks are provided, each having one of the months printed upon each face thereof. When the date bars 12 are changed, the month block is of course removed from the recess in the base bar and the block indicating the next ensuing month placed therein. The front face of the base bar 5 is also provided with an additional recess to receive a block 22 containing two numerals indicating the year, the first two numerals of 55 the year being printed upon the face of said bar. It will be understood that in order to change the year, the block 22 is simply removed and another block placed therein. Each of the bars 12 is also provided with a 60 series of wire loops or staples 23 projecting laterally therefrom opposite the several numerals on the bar. These staples are adapted to receive hooks formed upon the mem-

bers 24. These members have printed or otherwise indicated upon one of their faces, 65 the different phases of the moon.

From the foregoing description taken in connection with the accompanying drawing, it is believed that the construction, manner of use and several advantages of my invention will be clearly and fully understood.

70 It will be apparent that by the provision of the transposable date bars, the months may be easily and quickly changed and said bars properly arranged with respect to the week 75 day letters to disclose a month of any number of days.

75 The device provides a calendar which is neat and attractive in appearance, and of great convenience in practical use.

Owing to the extreme simplicity of my invention, it will be appreciated that the same can be produced at comparatively small manufacturing cost.

80 While I have shown and described the preferred construction and arrangement of the several elements employed, it will be understood that the device is susceptible of many minor modifications therein and I therefore reserve the privilege of resorting 90 to all such legitimate changes as may be fairly embodied within the spirit and scope of the invention as claimed.

Having thus described the invention, what is claimed is:

95 1. A perpetual calendar including a base provided with week day indicating characters, numeral carrying bars corresponding in number to said characters, pins fixed in the base, each of said bars being provided 100 with an opening in one end to receive one of said pins whereby the bars may be transposably arranged upon the base to indicate any month in a year, and means for retaining the numeral carrying bars upon the respective pins.

105 2. A perpetual calendar including a base provided with week day indicating characters, numeral carrying bars corresponding in number to said characters, a plurality of pins fixed in said base, a plurality of staples secured upon the base, said numeral carrying bars having openings in one of their ends to receive the respective pins and provided with studs upon their other ends for engagement in the respective staples whereby said bars may be transposably arranged upon the base to indicate any month in a year, and means for retaining said bars in position upon the base.

110 115 In testimony whereof I hereunto affix my signature in the presence of two witnesses.

120 GEORGE W. BAILEY.
